UNITED STATES PATENT OFFICE.

ODD T. AKRE, OF WALLINGFORD, IOWA.

WEATHER-STRIP.

No. 891,652.

Specification of Letters Patent. Patented June 23, 1908.

Application filed December 13, 1906. Serial No. 347,708.

To all whom it may concern:

Be it known that I, ODD T. AKRE, citizen of the United States, residing at Wallingford, in the county of Emmet and State of Iowa, 5 have invented certain new and useful Improvements in Weather-Strips, of which the following is a specification.

This invention is designed to provide novel means for excluding wind, dust, and dampness, and has for its object to provide an improved construction of weather strip which may be attached to the frame of a door, or window, or secured to the part to be rendered tight, said strip being devised with the special 15 view of coöperating with the stop of a door, or window, and comprising angularly disposed portions, one of which is confined by the stop, and the other extending in front of the stop so as to come between it and the 20 closure, whether the latter be a door, sash, or other like part.

For a full description of the invention and the merits thereof and also to acquire a knowledge of the details of construction of 25 the means for effecting the result, reference is to be had to the following description and accompanying drawings, in which

Figure 1 is a detail perspective view of a weather strip embodying the invention. 30 Fig. 2 is a similar view of a modification. Fig. 3 is a horizontal section of a door frame and door provided with a weather strip embodying the invention.

Corresponding and like parts are referred 35 to in the following description and indicated in all the views of the drawings by the same reference characters.

The weather strip comprises angularly disposed wings 1 and 2, the wing 1 being exceedingly thin and tapered to an edge away 40 from the wing 2.

The wing 2 is comparatively thick so as to maintain its proper shape and position, sustaining the wear of the moving part rubbing 45 thereover. The wings 1 and 2 are applied approximately at a right angle to each other so as to fit about the corner of a stop, or like strip as indicated most clearly in Fig. 3.

The tapered wing 1 is adapted to be confined 50 between the stop 3 and the frame 4 of the door, window, or like part. By having the wing 1 tapered to an edge, and of less width than the top it is not exposed when the

strip is in position, and without the necessity of recessing the top to receive it this being 55 plain on reference to Fig. 3, in which the edge of the stop 3 remote from the door, or closure 5, is in contact with the frame 4, thereby concealing the wing 1.

The outer face of the wing 2 may be of any 60 form in transverse section and may be concave as illustrated in Fig. 1, or convex as shown in Fig. 2.

When adapting the weather strip to a door, it is preferred to apply the form shown in 65 Fig. 1 to the upper and lower stops and to the stop against which the movable edge of the door closes. The form shown in Fig. 2 is applied to the stop adjacent to the hinged edge of the door, thereby admitting of the door 70 working upon the convex side when closing.

By having the form shown in Fig. 1 applied to the stop against which the free edge of the door closes, slamming of the door is obviated and a tight joint assured, since the 75 projecting edge of the wing 2 is adapted to be slightly compressed and thereby admits of the door being closed and latched.

The weather strip may be constructed of any material best adapted for the purpose 80 but it is preferred to form the same of pliable material, thereby admitting of rolling the strip and of the same conforming to the irregularities in the surface so as to insure a tight joint between the frame 4 and the stop 3 85 when in position.

The preferred material is rubber which is elastic and not affected by dampness. The strip is provided in any length and is adapted to be cut to fit a door, window, or other part 90 to be protected against the weather in the manner herein stated.

Having thus described the invention, what is claimed as new is:

The combination of a frame, a swinging 95 closure for the frame, a stop applied to the frame for limiting the movement of the swinging closure, and a weather strip co-operating with the stop, the said weather strip being formed of elastic material and 100 comprising two wings disposed at right angles to each other, one of the wings being clamped between the stop and the frame and being of less width than the stop, the said wing also gradually tapering in thickness 105 toward its outer edge to obviate the neces-

sity for recessing the stop, while the opposite wing bears against the edge of the stop and corresponds in width to the thickness of the same, the said opposite wing having a thickened formation and being adapted to be compressed against the stop by the swinging closure.

In testimony whereof I affix my signature in presence of two witnesses.
